CLAIM

The ornamental design for a combined children's play tent with attached bed sheet therefor, as shown and described.

DESCRIPTION

FIG. 1 is a perspective view of a combined children's play tent with attached bed sheet therefor showing my new design thereof;

FIG. 2 is a top elevational view shown in FIG. 1 thereof; FIG. 3 is a front elevational view as shown in FIG. 1 thereof; FIG. 4 is a left side elevational view as shown in FIG. 1 thereof;

FIG. 5 is a bottom elevational view thereof;

FIG. 6 is a front plan view side of FIG. 7 thereof;

FIG. 7 is a top plan view in an open condition of use thereof;

FIG. 8 is a side plan view of FIG. 9 thereof; and,

FIG. 9 is a bottom plan in an open condition of use thereof.

The rear view of FIG. 3 is a mirror image view thereof.

The right side of FIG. 4 is a mirror image view thereof.

The broken line shown in FIGS. 1, 2, 3, 4 exemplifying the "viewing aperture" is for illustrative purposes only and forms no part of the claimed design.
